[57] CLAIM

The ornamental design for a cylindrical smoking storage device, as shown and described.

DESCRIPTION

FIG. 1 is a front view of the preferred embodiment with the rear view, left side view, and right side view being mirror images thereof;

FIG. 2 is a bottom view;

FIG. 3 is a top view of the device in a closed state;

FIG. 4 is a top view in a first open state;

FIG. 5 is a top view in a second open state;

FIG. 6 is a front view of the device of FIG. 5 with the rear view being a mirror image thereof;

FIG. 7 is a left side view of the device of FIG. 5 with the right side view being a mirror image thereof;

FIG. 8 is a front view of a first alternate embodiment;

FIG. 9 is a rear view of the device of FIG. 8;

FIG. 10 is a left side view of the device of FIG. 8 with the right side view being a mirror image thereof;

FIG. 11 is a bottom view of the device of FIG. 8;

FIG. 12 is a top view of the device of FIG. 8 in a closed state;

FIG. 13 is a top view of the device of FIG. 8 in a first open state;

FIG. 14 is a top view of the device of FIG. 8 in a second open state;

FIG. 15 is a front view of the device of FIG. 14 with the rear view being a mirror image thereof;

FIG. 16 is a left side view of the device of FIG. 14; and,

FIG. 17 is a right side view of the device of FIG. 14.
